Primary Examiner — Sandra Snapp*Assistant Examiner* — Jasmine L. Comedy*(74) Attorney, Agent, or Firm* — Michael David Eisenberg(57) **CLAIM**

The ornamental design for a spliced floor as shown and described.

DESCRIPTION

FIG. 1 is a top, front, right side perspective view of a spliced floor, showing my new design;

FIG. 2 is a bottom, rear, left side perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof;

FIG. 8 is a front elevation view thereof;

FIG. 9 is an enlarged perspective view of the detail 9 shown in FIG. 1; and,

FIG. 10 is an enlarged perspective view of the detail shown in FIG. 2.

The dashed broken lines depict portions of the spliced floor that form no part of the claimed design.

The dot-dash broken lines in FIGS. 1, 2, 9 and 10 depict the boundaries of the enlargements and form no part of the claimed design.
